UNITED STATES PATENT OFFICE.

JAMES T. DOUGINE, OF CHICAGO, ILLINOIS.

WAGON-TONGUE SUPPORT.

SPECIFICATION forming part of Letters Patent No. 295,237, dated March 18, 1884.

Application filed November 3, 1883. (No model.)

To all whom it may concern:

Be it known that I, JAMES T. DOUGINE, a citizen of the United States, residing at Chicago, in the county of Cook and State of Illinois, have invented a new and useful Improvement in Tongue-Supporters for Wagons and other Vehicles, of which the following is a specification.

My invention relates to devices for supporting the tongues of vehicles.

The object of the invention is to provide a cheap, simple, efficient, and durable device for supporting the tongue, and which will allow the tongue at the same time to turn or swing around freely horizontally; and to this end my invention consists in supporting the tongue by means of a coil compression-spring and a curved rod secured to the bottom or end of the wagon-box, one end of the spring being connected to this curved rod by means of a hook or other device, so as to slide freely thereon as the tongue is turned, and the other end of the spring being fastened to the tongue.

In the accompanying drawings, which form a part of this specification, Figure 1 is a perspective view of a device embodying my invention. Figs. 2 and 3 are bottom views of the wagon box or body, showing the curved rod or rail attached, and Fig. 4 is a sectional elevation.

Similar letters of reference indicate like parts wherever used.

In the drawings, A represents the wagon or other vehicle body or box, and B the tongue hinged to the axle at b.

C is a curved rod or guide-rail secured to the bottom or other part of the body A by means of brackets c, attached to the under side of the rod C at one end, and secured at the other end, 40 by means of screws or bolts c', to the bottom A, interiorly of the curved rod C, so as not to interfere with the free sliding thereon of the compression-spring, which is suspended therefrom.

D is a coil-spring. The pull-rod d of the 45 spring is secured at one end to the tongue B by means of the bolt d', and at its other extremity to the flat end plate d'', which presses against or rests upon the opposite extremity of the coil-spring D, which surrounds the pull-rod. 50 The pull-rod d passes loosely through the end plate d'', and is secured thereto adjustably by

a nut, d³, the end of the rod d being threaded, by which means the tension of the spring may be adjusted. The other pull-rod, d⁴, is looped or doubled and passes through the eye of the hook d⁵, which fits over the curved rod C. Both branches of the pull-rod d⁴ pass through the coil-spring, and its two extremities are riveted or secured to the end plate d⁶, which presses against or fits over the other end of the coil-spring. The single pull-rod d passes through a hole in the middle of the end plate d⁶, and the double pull-rod d⁴ fits astride the end plate d⁶, the two end plates standing at right angles to each other, so that the end plates serve as guides to the sliding of the pull-rods upon each other, as well as to cause the pressure to come evenly and squarely upon the spring, and to stiffen or guide the coils in their contraction or expansion. As the hook d⁵ slides 70 or swings around on the curved rod C as the tongue turns in either direction, I am by this means enabled to attach the spring to the tongue, at a considerable distance from the point where it is hinged to the axle, thereby 75 obtaining a good lifting purchase, thus increasing the durability and efficiency of the spring and rendering it unnecessary to employ so strong a spring. If the fore wheels of the vehicle are adapted to turn under the body, the 80 curved rod C should be extended, so as to form a nearly complete or complete circle, as shown in Fig. 3, so as to permit the spring to swing completely around with the tongue.

In connection with my curved rod, I have 85 herein shown and described a coil compression-spring, as that I consider to be the best method known to me of practicing my invention; but other springs may be used, and some of the advantages of my invention may be secured by using a rigid connecting link or rod 90 to support the tongue from the curved rod C, instead of a spring.

In Fig. 1 I have shown in dotted lines the curved rod C secured to the end of the vehicle 95 box or body, which is a preferable mode of attachment in many vehicles. The rod C should be circular, so as not to raise or lower the end of the tongue as it swings around; but some of the advantages of my invention may be secured 100 if the rod has a different curve, or is even straight. The rod C may also in some cases

be attached to the bolster. The curved rod C, from which the connecting-spring is suspended, and upon which it slides as the tongue is turned, serves to throw the point of attachment of the connecting spring forward, so that the spring will occupy approximately a vertical position, as shown in Figs. 1 and 4, and at the same time permit of the lower end of the spring being attached to the tongue at a point sufficiently forward of its hinges to readily lift or support the tongue. The rod C being curved, and the connecting-spring D being adapted to slide around thereon as the tongue turns, the tongue will swing in a horizontal plane, though its point of attachment is, by means of said curved rod, brought a considerable distance in front of the king-bolt.

By use of the term "rod" or "curved rod" in this specification, and in the combination claimed, I do not wish to be understood as meaning or including thereby a mere strap or staple—such as that shown in Letters Patent No. 239,382, dated March 29, 1881—for securing the upper end of the spring to the bolster, because, obviously, a strap or staple does not, and can not serve to project the point of attachment of the spring forward of the king-bolt, nor to permit the upper end of the spring to describe a circle or an arc of a circle of any appreciable diameter around the king-bolt as

the tongue turns, and therefore such strap does not perform the function of the curved rod in my invention; and I wish it to be distinctly understood that I disclaim the device shown in said Patent No. 239,382, as forming no part 35 of my invention.

What I claim is—

1. In a vehicle-tongue supporter, the combination, with a curved rod or guide-rail secured to the vehicle box or body, of a connecting device suspended therefrom to the tongue, said connecting device being adapted to slide around on said curved rod as the tongue is turned, substantially as specified. 40

2. The combination, with a curved rod secured to the vehicle box or body, of a spring-connection to the tongue suspended from said curved rod, and adapted to slide around on the same as the tongue is turned, substantially as specified. 45

3. The vehicle-tongue supporter consisting of a rod secured to the vehicle, and a spring-connecting device attached to the tongue, and adapted to slide around on said rod as the tongue is turned, substantially as specified. 50

JAMES T. DOUGINE.
